UNITED STATES PATENT OFFICE.

WILLIAM W. HAWKINS, OF BROOKLYN, NEW YORK, ASSIGNOR TO WEBSTER ELECTRIC COMPANY, OF RACINE, WISCONSIN, A CORPORATION OF WISCONSIN.

IGNITION SYSTEM.

Application filed February 20, 1922. Serial No. 537,982.

To all whom it may concern:

Be it known that I, WILLIAM W. HAWKINS, a citizen of the United States, and resident of Brooklyn, in the county of Kings 5 and State of New York, have invented a certain new and useful Improvement in Ignition Systems, of which the following is a full, clear, concise, and exact description, reference being had to the accompanying 10 drawings, forming a part of this specification.

My invention relates to an ignition system which includes a specially wound magneto of either the movable or stationary armature type.

The armature or coil carrying element of the magneto carries two primary windings and a secondary winding, one of the primary windings preferably comprising a greater 20 number of turns than the other primary winding. The secondary winding is connected in a high tension circuit in the usual or any suitable manner. The primary windings are connected with a suitable condenser 25 and breaker mechanism which co-operates with the primary windings in a novel manner presently to be explained.

In the accompanying drawings illustrating my invention,

30 Figure 1 is a diagram illustrating my invention applied to an ignition system embodying a magneto of the rotating armature type; and

35 Figure 2 illustrates my invention applied to an ignition system including a magneto which comprises rotating inductors and a relatively stationary core structure upon which the windings are mounted.

Similar characters of reference refer to 40 similar parts throughout the several views.

Referring first to Figure 1, reference numeral 10 indicates a magneto comprising magnet 11, pole pieces 12, and a rotating armature 13 of the familiar H-type. The magneto need differ essentially from well known 45 types of rotating armature machines only with respect to the windings employed; hence, the magnet, pole pieces, armature, condenser and interrupter mechanism have 50 been diagrammatically illustrated. The condenser is illustrated at 14 and the interrupter mechanism at 15. At 16 is illustrated a grounding switch which is closed only when the system is to be put out of commis- 55 sion. At 17 is illustrated a conventional

distributor mechanism adapted to distribute high tension current to spark plugs 18, in the usual manner.

The core of armature 13 carries primary windings A and B and a secondary winding 60 C which consists of a large number of turns of wire smaller than that used in the primaries. In accordance with my invention, primary B preferably consists of a greater number of turns than primary A. For instance, primary B may comprise twice as many turns as primary A. In practice, the windings A, B and C are arranged concentrically, but in Figure 1, for clearness, I have illustrated the primary windings A 70 and B as disposed end to end upon the core which is common to all of the windings.

Winding C is connected in the secondary or high tension circuit of the ignition system in the usual manner, one end of said winding being grounded, and the other end thereof being connected with the flyer of distributor 17. One end of each of the primary windings is grounded, the insulated terminals of these windings being brought together as illustrated. When the interrupter contacts are closed, the insulated terminals of the primary windings are grounded. The condenser, connected on one side 80 with the insulated interrupter contact, and on the other side with ground, serves to prevent arcing at the contacts, and likewise co-operates with the primary windings as will presently appear. Switch 16 is closed only 85 when the system is to be put out of commis- 90 sion.

The distributor and interrupter mechanism are, of course, operated in timed relation to the magneto rotor, the interrupter being arranged to open twice during each 95 revolution of the rotor. In the magneto shown in Figure 1, the interrupter contacts preferably open each time the trailing edges of the armature are leaving the pole pieces.

Now let us assume that the magneto of 100 Figure 1 is in operation, and that the trailing edges of the armature are about ready to leave the pole pieces. A current wave is created in each of the primary windings, but at this time neither of these waves interferes with the other because each of the primary windings is short circuited through ground. When the interrupter opens, 105 ground is disconnected from the insulated terminals of the primary windings. When 110

2

this occurs, the current present in the larger primary winding B, augmented by a discharge from condenser 14, surges through the primary A. The current which thus 5 surges through primary A flows in the direction opposite to the direction of the current generated in primary A prior to the opening of the contacts. Primary A, therefore, tends to change its polarity in opposition to the flow of flux as established in the armature by the pole structure of the machine and, in all probability, the electromagnetic field built up around coil B prior to the opening of the interrupter contacts dies 10 rapidly away. At any rate, the herein described operation of the magneto causes the induction in the secondary winding C of a high tension ignition current capable of producing ignition sparks far superior to 15 those which can be procured by the use of a magneto of the conventional type employing a single primary winding. A high tension ignition current is induced in secondary C twice during each revolution of armature 13.

20 25 In Figure 2 I have diagrammatically illustrated the improvements of my present invention applied to an ignition system which includes a well known type of magneto embodying a stationary armature or coil carrying structure and rotors or inductors which, when operated, reverse the direction of flux flow through the stationary coil carrying structure. So far as my invention is concerned, the ignition system illustrated in 30 35 Figure 2 functions in exactly the same manner as does the system illustrated in Figure 1. I shall, therefore, refrain from describing the details of the magneto shown in Figure 3, but will state that a magneto of this kind is shown and described in United 40 States Reissue Patent, Number 14,373, dated October 2, 1917.

I appreciate that my present theory, hereinbefore explained, with respect to the reasons for the excellent performance of the system herein shown and described may be somewhat incomplete. I do know, however, that the ignition system herein described 45 delivers exceptionally hot sparks.

50 While I prefer to provide the primary winding B with more turns than primary A, I appreciate that a suitable arrangement providing a mere excess of capacity in coil B would operate in much the same manner.

This statement also holds true regarding a 55 construction wherein the primaries A and B are identical with respect to both capacity and number of turns.

Having thus illustrated and described by invention, I do not limit myself to the particular construction and arrangement of parts herein shown and described, but wish to claim all practical embodiments of the invention defined by the appended claims.

What I desire to secure by Letters Patent 65 and what I claim is:

1. In a magneto, a rotor and a stator, one of said magneto elements comprising a core, a primary winding comprising two generating coils wound about said core in the same 70 direction, corresponding ends of said coils being grounded, an interrupter having one contact grounded and the other contact connected to the non-grounded ends of said coils, and a secondary coil in inductive relation to said primary coils and core, but conductively separated therefrom.

2. In a magneto, a rotor and a stator, one of said magneto elements comprising a core, a primary winding comprising two generating coils wound about said core in the same 80 direction, corresponding ends of said coils being grounded, an interrupter having one contact grounded and the other contact connected to the non-grounded ends of said coils in parallel, a condenser in bridge of 85 said interrupter contacts, and a secondary coil in inductive relation to said primary coils and core, but conductively separated 90 therefrom.

3. In a magneto, a rotor and a stator, one of said magneto elements comprising a core, a primary winding comprising two generating coils wound around said core in the same direction, one of said windings comprising a greater number of turns than the other, corresponding ends of said coils being grounded, an interrupter having one contact grounded and the other contact connected to the non-grounded ends of said coils in parallel, a condenser in bridge of 95 said interrupter contacts, and a secondary coil in inductive relation to said primary coils and core, but conductively separated therefrom.

In witness whereof, I hereunto subscribe 100 my name this 27th day of January, 1922.

WILLIAM W. HAWKINS,
